UNITED STATES PATENT OFFICE.

GEORGE T. FLICK, OF PHILADELPHIA, PENNSYLVANIA, ASSIGNOR TO OTTO SCHWEGLER, OF PHILADELPHIA, PENNSYLVANIA.

HOSIERY-FINISHING BOARD.

1,075,846.

Specification of Letters Patent. Patented Oct. 14, 1913.

Application filed September 14, 1912. Serial No. 720,524.

To all whom it may concern:

Be it known that I, George T. Flick, a citizen of the United States, residing in the city and county of Philadelphia, State of Pennsylvania, have invented a new and useful Hosiery-Finishing Board, of which the following is a specification.

In hosiery finishing boards as ordinarily constructed of wood considerable difficulty has arisen in practice owing to the warping and splintering of the boards which causes many dozens of seconds or imperfect stockings to be made in a day's production. It has further been found in practice that when wooden boards are employed a separate lot of boards are necessary for finishing silk work, a separate lot of boards are necessary for finishing cotton hose, and a separate lot of boards are required for finishing delicate colors such as white, pink and blue. It has also been found in practice that the life of a wooden board is comparatively short owing to the shrinking in length and width so that the same after awhile cannot be used for standard sizes. It has further been found necessary when the ordinary type of wooden board has been employed to employ skilled labor to operate the same and since a wooden board takes a considerable time to dry, it has been necessary to employ an excessive amount of steam.

With the above ends in view, my invention consists of a novel construction of a novel hosiery finishing board, comprising a metallic body portion and a handle of heat resisting material detachably connected therewith, said board embodying other novel features of construction, all as will be herein-after fully set forth and particularly pointed out in the claims.

It further consists of other novel features of construction all as will be hereinafter fully set forth.

For the purpose of illustrating my invention, I have shown in the accompanying drawings one form thereof which is at present preferred by me, since the same has been found in practice to give satisfactory and reliable results, although it is to be understood that the various instrumentalities of which my invention consists can be variously arranged and organized and that my invention is not limited to the precise arrangement and organization of these instrumentalities as herein shown and described.

Figure 1 represents a plan view of a

hosier finishing board embodying my invention. Fig. 2 represents a side elevation of Fig. 1. Fig. 3 represents a section on line xx Fig. 1. Fig. 4 represents a side elevation of the handle in detached position. Fig. 5 represents a sectional view of another embodiment of my invention showing the manner of forming a board when the groove is to be on the opposite side of that seen in Fig. 3. Fig. 6 represents a sectional view on an enlarged scale of a portion of Fig. 1. Fig. 7 represents a perspective view of the fastening nut.

Similar numerals of reference indicate corresponding parts in the figures.

Referring to the drawings:—1 designates a hosiery finishing board embodying my invention, the same being provided with a leg portion 2 and a foot portion 3 which are formed of a thin metal sheet or plate and preferably of aluminum or its equivalent. The board is provided on one side near one edge with a groove 4 which is located a desired distance from an edge of the finishing board, and in the present instance extends from the top of the leg around the heel portion of the board and terminates at the toe end of the board. The purpose of this groove is to receive the seam of the stocking or hosiery and prevent the latter from shifting while the stocking is shrinking during the finishing process; and owing to the provision of this groove, my novel hosiery board may be operated without the necessity of employing skilled labor.

The board 1 is provided with a desired number of apertures 5 through which are adapted to pass the fastening bolts 6, which latter also pass through an apertured plate 12 and through apertures 7 in the bifurcated end 8 of a grasping handle 9, said bolts passing through the apertured plate 10 and being provided with nuts 11 whereby the grasping handle 9 is detachably connected with the body portion of the board. This grasping handle 9 is preferably made of asbestos or other heat resisting material so that the operator is not liable to burn his hands when the form is in the finishing oven.

It will be apparent that my novel finishing board will have practically no wear thereon except at the point where the handle is attached which will be very slight and the board will retain its shape and will not vary in size by continuous use.

It will be noted that in the present in-

stance I have shown the handle portion 9 as being grooved in order to receive the apertured plates 12 and 10 so that such plates will be flush with the outer surface of the 5 grasping handle. The nuts 11 are adapted to be received in the recessed portion of the apertured plate 10, so that said nuts are flush with the outer face of the grasping handle 9, as will be clearly understood by 10 reference to Figs. 2 and 6. Any desired type of fastening device may be employed, and the nut 11, as seen in Fig. 7, is provided in the present instance with openings 13, whereby the same is adapted to be actuated 15 by an ordinary spanner wrench.

Since the board is smooth and thin, it has been found in practice that a saving of 24 inches of cotton or silk in every dozen manufactured can be obtained over the use of 20 the ordinary wooden board; for example, where a stocking is made 28 inches long it is only necessary to make the same 27 inches long.

There is no possibility of the metal board 25 warping or splintering and it is therefore impossible to make seconds by making holes in the goods when they are being placed on the boards.

It will be further apparent that since the 30 metal finishing board does not absorb the moisture it will dry in a very much shorter time than is required with a wooden board and a smaller amount of steam is necessary than is the case with a wooden board.

35 The groove 4 may be located on either side of the finishing board, and in practice both right and left hand finishing boards are employed so that it will be understood that it is within the scope of my invention to 40 employ such groove either on the right or left hand side of the board, as will be understood by reference to Figs. 3 and 5 of the drawing.

It will now be apparent that I have de- 45 vised a novel and useful construction of a hosiery finishing board which embodies the features of advantage enumerated as de-

sirable in the statement of the invention and the above description, and while I have, in the present instance, shown and described 50 a preferred embodiment thereof which has been found in practice to give satisfactory and reliable results, it is to be understood that the same is susceptible of modification in various particulars without departing 55 from the spirit or scope of the invention or sacrificing any of its advantages.

Having thus described my invention, what I claim as new and desire to secure by Letters Patent, is:—

60 1. A hosiery finishing board consisting of a metal sheet, and a handle detachably connected therewith.

2. A hosiery finishing board consisting of a metal sheet, and a handle of heat resist- 65 ing material connected therewith.

3. A hosiery finishing board having a single groove on one side in proximity to its rear edge and extending from the leg portion to the end of the toe portion.

70 4. A hosiery finishing board consisting of a thin metallic sheet conforming to the shape of the stocking and having a single groove in its side substantially parallel with the rear edge of the board.

5. A hosiery finishing board consisting of a sheet of material having a groove in one side adapted to receive a seam, and a grasping handle detachably connected with said board.

80 6. A hosiery finishing board having a seam receiving groove in one side thereof, and an asbestos grasping handle connected with said board.

7. A hosiery finishing board having a 85 seam receiving groove in one side thereof, a grasping handle having a bifurcated end to receive said board, and fastening devices passing through said board and said bifurcated end.

GEORGE T. FLICK.
